CAN

Harry Sebell, Boston, Mass., assignor of one-half
to Arthur H. Parker, Lexington, Mass.

Application September 27, 1934, Serial No. 745,731

4 Claims. (Cl. 220—60)

This invention relates to containers having removable and replaceable covers and particularly to means for locking or retaining the cover on the container body.

5 The invention is herein illustrated as applied to a container in the form of a can and in the following description the container is referred to as a can. This invention, however, is not limited to containers of the can type but may 10 be applied to other types of containers.

In accordance with the present invention the cover for the container is constructed so that normally it has an outwardly-curved shape, but when pressure is applied thereto the outwardly-curved portion will snap by a neutral or central position into a concavely-curved position, the movement from the convexly-curved normal position into the concavely-curved position taking place with a snap action.

20 One of the objects of the invention is to provide a novel construction by which a cover of this type will be locked to the can body when it is forced or sprung from the convexly-curved position to the concavely-curved position, and 25 will be unlocked from the can body by a pulling force applied thereto sufficient to spring the cover from the concavely-curved shape to the convexly-curved shape.

20 In carrying out my invention I provide the can body with an interior downwardly-facing shoulder at its open end, and I also provide the cover with a locking element adapted to be forced underneath the shoulder when the cover is forced from the convex shape into the concave shape, thereby locking the cover to the can body, and to be withdrawn from said shoulder, thereby unlocking the can cover by the movement from the concave shape to the convex shape.

40 The operation of locking the cover to the container, therefore, involves simply spacing the cover in position on the container and then applying sufficient pressure to the cover to spring it from the convex shape into the concave shape. 45 Similarly, the operation of unlocking and removing the cover involves simply applying sufficient pulling force to the cover to spring it from the concave shape to the convex shape, thereby unlocking the cover and then removing 50 the cover in the ordinary way.

In order to give an understanding of the invention, I have illustrated some embodiments thereof in the accompanying drawings which will now be described.

55 In the drawings:

Fig. 1 is a sectional view of a cover for a can body showing one form of my invention.

Fig. 2 is a partial sectional view of a can body adapted for use with the can cover shown in Fig. 1, said Fig. 2 showing the cover in dotted

lines as it is first applied to the can but before it is locked thereto.

Fig. 3 is a sectional view showing the can cover locked to the can.

Fig. 4 is an underside view of the cover.

Fig. 5 is a sectional view showing a cover having a different embodiment of my invention.

Fig. 6 is a view similar to Fig. 2.

Fig. 7 is a sectional view showing the cover illustrated in Fig. 5 locked to the can body.

Fig. 8 is an underside view of the cover shown in Fig. 5.

Fig. 9 is a view similar to Figs. 1 and 5 but illustrating a different embodiment of the invention.

Fig. 10 shows a portion of a can body with which the cover shown in Fig. 9 is adapted to be used.

Fig. 11 is a sectional view showing the cover illustrated in Fig. 9 locked to the can body.

Fig. 12 is an underside view of the cover shown in Fig. 9.

Referring first to Figs 1 to 4, 1 indicates a portion of a can body and 2 indicates generally a cover or can end embodying one form of my invention and which is designed to be used with the can body 1. The can body 1 has the open end 3 and it is provided at its open end with an interior downwardly-facing locking shoulder 4. This shoulder can be formed in various ways 30 without departing from the invention. One convenient way is to roll or curl the top edge of the can body over in an inward direction to form the interior bead 5, the under face of the bead constituting the locking shoulder 4.

The cover 2 is constructed with an annular portion 6 adapted to rest on and engage the top edge 7 of the can body, and the central portion of the cover has an outwardly-curved or "bumped" shape as seen in Fig. 1, and the cover 40 is so made that when pressure is applied thereto, the central portion thereof will be sprung or snapped into an inwardly or concavely-curved shape as shown in Fig. 3.

The cover is also constructed with a locking 45 portion 8 which is adapted to interlock with the locking shoulder 4 to lock the cover to the can and the construction is such that when the can cover is snapped or forced from its convexly-curved shape into its concavely-curved shape the locking portion 8 is expanded sufficiently in a radial direction to bring it into interlocking engagement with the locking shoulder of the can body.

In the embodiment shown in Figs. 1 and 4 the locking portion 8 is formed at the lower ends of arms 12 depending from the under face of the cover 2, each arm having at its lower end a lip or bead forming part of the entire locking portion 8. These arms 12 may be provided for in various 60

ways. In the construction shown in Figs. 1 to 4, said arms 12 are formed as sections of a skirt or flange 9 which depends from the under face of the cover, said flange being slit vertically as shown at 11 to provide the separate arms 12. The lower edge of the skirt 9, and consequently the lower end of each arm 12 is curled over to form a bead which provides the locking portion 8. The skirt or flange 9 from which the arms 12 are formed is rigidly connected to the cover so that when the cover is changed from the convex shape shown in Fig. 1 to the concave shape shown in Fig. 3, the skirt 9 will be expanded slightly and the arms will move outwardly in a radial direction.

The arms 12 are formed in the first instance so that when the cover is applied to the open end of the can as shown in dotted lines Fig. 2, the locking portion 8 will be entered through the bead 5 on the can. After the can cover has been placed in position on the can end, then sufficient pressure is applied to the cover to cause the central portion thereof to spring or snap from its outwardly or convexly curved position shown in Fig. 1 to the depressed or concavely curved position shown in Fig. 3. This shifting of position of the central portion of the can cover causes the lower ends of the arms to move outwardly, thereby bringing the locking portion 8 underneath and into locking engagement with the locking shoulder 4 as shown in Fig. 3.

The cover illustrated in Fig. 1 is provided with a rim or exterior skirt portion 13 which embraces the top edge of the can. If the can is to be tightly sealed, I propose to employ a sealing gasket 14 between the portion 6 of the cover and the top edge 7 of the can body. This gasket may be in the form of a sealing compound applied either to the annular portion 6 of the cover or to the top edge 7 of the can body as is commonly done in sealing tin cans.

In order to open the can, the first operation is to apply a sufficient pulling force to the can cover to snap it from the depressed or concavely curved shape shown in Fig. 3 to the "bumped" or convexly curved shape shown in Fig. 1, this operation serving to withdraw the locking portion 8 of the cover from under the locking shoulder 4. Continued pulling force applied to the cover will then separate it from the can body. To facilitate this change in shape of the cover, I will preferably provide it with a ring 15. This ring not only provides means by which the necessary pulling force may be applied to the can cover to unlock it from the can, but also provides means for removing the cover from the can. After the can has been opened and some or all of the contents have been discharged, the cover may be then replaced on the can and locked thereto by the simple operation of applying sufficient force to the cover to change the shape thereof from the convexly curved shape of Fig. 1 to the concavely curved shape of Fig. 3. My improved cover, therefore, is a replaceable one which can be removed as often as desired, and which may be readily locked to the can each time it is replaced thereon.

If the can is one which is hermetically sealed and one in which vacuum conditions exist inside the can, it may be necessary to break the vacuum before the cover can be removed. To provide for this I propose to secure the ring 15 to an anchoring member 16 which has a stem portion 17 extending through the cover and a head portion 18 on the inside of the cover. This head portion

18 can be soldered to the cover as shown at 40 in such a way as to make a non-leakable joint, but so that when a twisting force is applied to the ring 15, the soldered connection 40 between the head portion 18 and the underside of the can cover will be broken. If, therefore, the can is one which has the vacuum conditions inside, the breaking of the vacuum can be accomplished by twisting the ring 15, and thereby breaking the soldered connection between the anchoring member 16 and the cover. This will allow sufficient air to enter the can to destroy the vacuum, and when the cover has been unlocked by changing its shape from that shown in Fig. 3 to that shown in Fig. 1, the cover can be readily removed.

In Figs. 5 to 8 I have shown a different embodiment of the invention in which the locking portion of the cover is integral therewith instead of being formed on a separate piece soldered thereto.

In said Figs. 5 to 8, 1 indicates the can body which is similar to that shown in Fig. 2, it having the interior bead 5 at its open end which provides the downwardly-facing interior locking shoulder 4. The can cover is shown at 19 and in forming the cover the peripheral portion of the blank from which the cover is made is bent inwardly as shown at 20 and then downwardly as shown at 21 to provide a skirt portion, the lower edge 22 of which is formed with a rib 23 or bead that constitutes the locking portion of the can cover. This skirt portion 21 is provided with the slits 23 so that the skirt is resilient in a radial direction, these slits dividing the skirt into separate sections 24, each of which has a locking portion 22 at its lower edge. In this form of can cover the two-ply peripheral portion 25 is the annular portion which engages the top edge 7 of the can body and the separate sections 24 of the skirt 21 formed by the slits 23 constitute arms which depend from the can cover, and which are provided at their lower ends with the bead or lip 22 which constitutes the locking portion. In this embodiment also the change in shape of the cover from the convex shape to the concave shape causes the arms 24 to move outwardly to bring the lower ends thereof into locking engagement with the locking shoulder of the can body. The cover shown in Figs. 5 to 8 is also provided with the pull ring 15 as in the other embodiment of the invention. The can cover shown in Figs. 5 to 8 operates in the same way as that shown in Figs. 1 to 4. In applying the cover to the can body the cover is first put in position as shown in Fig. 5, during which operation the resilient skirt 23 and the locking portion 22 is entered into the mouth of the can body through the bead 5. The cover is made so that it normally has the outwardly curved shape shown in Fig. 5, and when the cover has been applied to the can body, then pressure is applied to the central portion of the cover to snap it from the outwardly curved shape shown in Fig. 5 into the inwardly or concavely curved shape shown in Fig. 7. This change in shape causes the locking portion 22 to expand outwardly into locking engagement with the locking shoulder 4 as clearly seen in Fig. 7.

The can may be opened by first applying a pulling strain to the ring 15 which will snap the cover from the concavely curved shape into the convexly curved shape, thereby contracting the locking portion 22 and withdrawing it from locking engagement with the shoulder 4. The

cover then may be removed by applying further pulling strain to the ring 15.

In Figs. 9 to 12 I have shown a different embodiment of the invention. In this embodiment 5 the can body which is indicated at 26 is formed at its open end with the interior downwardly-facing shoulder 27, and this shoulder may be formed conveniently by providing the top edge 10 of the can with the interior bead 28. The can body is deformed also by providing it with the interior rib 29 directly below the downwardly-facing shoulder 27. The can cover is indicated at 30 and it is shown as provided with the annular grooved portion 31 to receive the bead 28 15 at the top edge of the can, and with the skirt portion 32 to embrace the upper end of the can. In the construction shown in Fig. 9 the locking portion of the can cover is in the form of a plurality of radial arms 33 which are rigidly secured 20 at their inner ends to the underside of the cover as shown at 34, the outer end 35 of each arm being free from the cover and slightly spaced therefrom. These locking arms 33 have such dimension that when the cover is applied 25 to the can body the arms will enter the open end of the can and rest against the upper face of the rib 29 as shown by dotted lines in Fig. 10. The cover 30 is made so that while normally it has the convexly-curved shape shown in Fig. 9, yet 30 when pressure is applied thereto, it will snap or spring into the concavely-curved shape shown in Fig. 11. This change of shape from the convex curvature to the concave curvature causes a slight outward movement of the ends of the locking 35 arms 33 which forces them under the locking shoulder 27 as shown in Fig. 11. This interlocking of the locking arms with the locking shoulder is assisted by the engagement of the ends of the arms with the upper face of the rib 40 29 during the snapping of the cover from the convex shape to the concave shape.

When the can is to be opened, a pulling force is applied to the pull ring 15 which first snaps the cover from the concave shape of Fig. 11 to the 45 convex shape of Fig. 9, thereby withdrawing the ends 35 of the locking arms from beneath the locking shoulder 27. A further pull on the pull ring will remove the cover entirely from the can body.

50 In all embodiments of the invention the can body is provided with an interior locking shoulder, and the cover is provided with an expansible locking portion adapted to engage the locking shoulder and is constructed so that such engagement is effected by applying a pressure to the cover in an axial direction, thereby snapping or springing the cover from the convex shape to the concave shape. In all embodiments of the invention also the removal of the cover involves first applying a pulling force thereto to snap it from the concave shape to the convex shape, which operation withdraws the locking portion of the cover from locking engagement with the locking shoulder, and then continuing 55 the pulling force on the cover to withdraw it from the can body. My improved cover is not only adapted to seal the can in the first instance, but is capable of use as a replaceable cover since it can be readily replaced on the can after it has been opened, and can be locked to the can simply by snapping the cover from the convex shape to the concave shape.

75 While I have illustrated in the drawings several embodiments of the invention and have also shown the invention as applied to a container in

the form of a can, yet the invention is not limited to the construction shown nor to a container in the form of a can as it will be obvious that the principle of the invention may be embodied in other structures and containers other than cans made of sheet metal. Hence, in the specification and claims the term "can" is used in a general sense as meaning any suitable container to which the invention is applicable.

I claim:

1. A can construction comprising a can body having an interior annular locking shoulder at its open end, a cover normally having a convex curvature but adapted to be forced into a concave shape with a snap action, a locking element 10 carried by the cover and adapted to be forced into locking engagement with the locking shoulder by the movement of the cover from the convex shape to the concave shape, an anchoring member extending through the cover and hermetically sealed thereto by an easily disruptable connection and a pull ring secured to said anchoring member whereby a twisting force applied to the pull ring will break the hermetic seal.

2. A can construction comprising a can body 25 having an interior annular locking shoulder at its open end, a cover which normally has a convex curvature but is adapted to be forced into a concave shape by pressure applied thereto, an annular locking element carried by the cover and 30 adapted to be forced into locking engagement with the locking shoulder by the movement of the cover from the convex shape to the concave shape, and a pull ring connected to the cover with an easily disruptable hermetic seal whereby 35 a pulling force applied to the pull ring will snap the cover from its concave to its convex shape and a twisting force applied to the pull ring will break the hermetic seal.

3. A can construction comprising a can body 40 having an interior locking shoulder at its open end and also having an interior bead below the locking shoulder, a cover which is normally convexly-curved but is adapted to be sprung into a concavely-curved shape and a plurality of radially-extending locking arms secured to the underside of the cover, the outer ends of the arms being forced outwardly into locking engagement with said shoulder by the movement of the cover from the convex shape to the concave 45 shape, the ends of said arms, when in locking position, being confined between said shoulder and said bead.

4. A can construction comprising a can body having an interior locking shoulder at its open 55 end and also having an interior bead below the locking shoulder, a removable and replaceable cover which is normally convexly-curved but is adapted upon application of pressure thereto in one direction to be sprung into a concavely-curved shape, and upon application of pressure thereto in the opposite direction to be sprung into the convexly-curved shape and a plurality of radially extending locking arms secured to the underside of the cover, the outer ends of 60 the arms being forced outwardly into locking engagement with said shoulder by the movement of the cover from the convex shape to the concave shape, said ends of the arms being withdrawn from locking engagement with the shoulder by the movement of the cover from the concave shape to the convex shape, the ends 65 of said arms, when in locking position, being confined between said shoulder and said bead.
